CLAIM

The ornamental design for a vacuum cleaner housing, as shown and described.

DESCRIPTION

FIG. 1 is a front perspective view of a vacuum cleaner housing showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

Portions of the bottom not shown in either FIG. 7 or any other figure form no part of the claimed design.

The details shown in broken lines in all views are for illustrative purposes only and form no part of the claimed design.
